UNITED STATES PATENT OFFICE.

CHARLES BERGMANN, OF PITTSBURG, PENNSYLVANIA, ASSIGNOR OF ONE-FOURTH TO EDWARD BARRY, OF JOHNSTOWN, PENNSYLVANIA, AND ONE-FOURTH TO MICHAEL H. DENNEHY AND ONE-FOURTH TO MICHAEL DWYER, OF PITTSBURG, PENNSYLVANIA.

SELF-CLOSING FAUCET.

No. 851,487.

Specification of Letters Patent.

Patented April 23, 1907.

Application filed March 31, 1906. Serial No. 309,094.

To all whom it may concern:

Be it known that I, CHARLES BERGMANN, a citizen of the United States, residing at Pittsburgh, in the county of Allegheny and State of Pennsylvania, have invented certain new and useful Improvements in Self-Closing Faucets, of which the following is a specification.

This invention relates to that class of valves, taps and the like which are designed to automatically resume a closed position after having been opened for drawing off water or other liquid.

To this end the invention contemplates a simple and thoroughly practical construction of self-closing faucet which is positive and reliable in its action, while at the same time having an entire absence of packing or valve disks.

A further object is to provide an improved construction wherein provision is made against leakage or waste of the fluid.

With these and other objects in view which will more readily appear as the nature of the invention is better understood, the same consists in the novel construction, combination and arrangements of parts hereinafter more fully described, illustrated and claimed.

In the drawings—Figure 1 is a sectional view of a self-closing faucet embodying the present invention, and illustrating a type of valve or draw-off device possessing special utility as a beer-tap. Fig. 2 is a modification of a horizontal form of tank-faucet or the like embodying the present invention.

Like references designate corresponding parts in the several figures of the drawings.

In the preferable embodiment of the invention shown in Fig. 1 of the drawings, the same includes in its general organization, a valve-casing 1 provided with a smooth interior slide-bore preferably of uniform diameter throughout. The said casing 1 may consist of a plain casting bored and reamed out to form the slide-bore 2 and provided with an inlet tube or neck 3 in communication with the interior bore. The said inlet tube or neck is fitted to the barrel tank or other liquid container for the purpose of conducting the fluid into the valve casing. The slide-bore 2 of the latter is designed to accommodate therein a reciprocal valve-plug 4 which is turned to a registering sliding and

non-leaking fit with the wall of the said bore 2, whereby extra packing valve disks or equivalent element are entirely dispensed with. The said reciprocal valve-plug 4 is provided therein with a longitudinal fluid passage 5 opening through one end of the plug, and at an intermediate point in the body of the latter communicates with a side port 6 adapted to be moved in and out of register with the side casing port 7 with which communicates the inlet tube or neck 3 of the valve casing. The said valve plug 4 is further provided for a portion of its length with a reduced guiding-stem 8 slidably working through the guide opening 9 of a retaining nut 10, detachable screwed or otherwise fitted in the lower open discharging end of the casing 1. The said nut 10 also acts as a discharge nipple, and as an abutment for one end of the retractile closing spring 11 coiled about the stem 8 and whose other end exerts a closing pressure against the rest shoulder 12 formed on the valve-plug at one end of the reduced stem 8.

The plug body 4 is formed in one side thereof with a longitudinal key-way 13 receiving a retaining pin or key 14 fitted in the side of the casing and serving to prevent the valve from turning. At the same time the said key-way provides a circulating passage for the air when the spring is compressed so that the air may circulate into the top part of the casing and thereby avoid compression of the air in the spring receiving space with a consequent interference with the free opening of the valve.

At one end of the valve-plug is provided with a handle-stem 15 working through the detachable casing-cap 16 at the upper end of the casing and having fitted thereon a suitable handle or hand-knob 17.

To open the valve, it is simply necessary to press the valve-plug inward to bring the ports 6 and 7 in register. Upon the release of the hand pressure, the spring automatically carries the valve-plug to a closed position.

In the modification shown in Fig. 2 exactly the same construction and action of parts is involved excepting that the valve-casing is arranged horizontally with the guide and abutment 10^a formed integrally therewith and the inlet 18 provided at one end of

the casing and the outlet 19 in one side, the latter being designed to register with the side port 6 of the valve-plug.

What I claim is—

- 5 A self-closing faucet comprising a valve casing having an interior slide-bore and provided at one end with an open guide, said casing being also provided with a side port, a reciprocating valve plug slidably registering with the bore of the casing and provided with a reduced guiding stem sliding in the guide in one end of the casing, said plug being further provided with a longitudinal fluid passage

and side port, and in its external surface with a longitudinal combined key-way and air 15 circulating groove, a fixed retaining key engaging said key-way, and a closing spring housed within the casing and engaging the valve plug.

In testimony whereof I hereunto affix my 20 signature in the presence of two witnesses.

CHARLES BERGMANN.
